(57) **CLAIM**

The ornamental design for a slim plug outlet as shown and described.

DESCRIPTION

FIG. 1 is a top, front left perspective view of a slim plug outlet showing our design;

FIG. 2 is a left view thereof;

FIG. 3 is a right view thereof;

FIG. 4 is a front view thereof;

FIG. 5 is a rear view thereof;

FIG. 6 is a bottom plan view thereof; and,

FIG. 7 is a top plan view thereof.

The slim plug outlet is shown with a symbolic break in its length. The appearance of any portion of the article beyond the break line forms no part of the claimed design.
